UNITED STATES PATENT OFFICE.

FRANK J. SENG, OF CHICAGO, ILLINOIS, ASSIGNOR TO THE SENG COMPANY, A CORPORATION OF ILLINOIS.

EXTENSION-TABLE.

No. 885,962.

Specification of Letters Patent. Patented April 28, 1908.

Application filed March 2, 1907. Serial No. 360,160.

To all whom it may concern:

Be it known that I, FRANK J. SENG, a citizen of the United States, residing at Chicago, in the county of Cook and State of Illinois, have invented certain Improvements in Extension-Tables, of which the following is a specification.

This invention is an improvement in extension tables, and relates more especially to the class of pedestal extension tables, in which the pedestal is divided or formed in two sections which support the extensible sections of the top and are adapted to come together or meet when the table is closed and thereby form a central pedestal or pillar. In this type of table it is a common fault for the pedestal sections to sag or spread apart at their lower ends, after being used to some extent, resulting in a widening crevice or crack between said sections and extending to the lower ends thereof. This unsightly crevice or crack will gradually widen as the table is used, and therefore numerous devices have been provided for adjusting the pedestal sections on a line with each other so that they will properly come together and form a close joint throughout the length of the pedestal or pillar.

The principal objects of my invention, therefore, are to provide a device for adjusting the pedestal sections of an extension table that is simple in construction and therefore cheap to manufacture, may be easily applied to any of the ordinary forms of pedestal extension tables, and when applied can be easily and conveniently operated to secure any degree of adjustment and thereby insure a proper joint between said sections.

The invention consists in the construction, combination and arrangement of parts hereinafter particularly described and specifically set forth in the appended claims.

In the drawings accompanying this specification: Figure 1 is a side elevation, partly in section, showing the application of the invention, and illustrating only those parts to which the devices are adapted to be applied. Fig. 2 is a sectional view on the line 2—2 of Fig. 1. Fig. 3 is a sectional view on the line 3—3 of Fig. 1. Fig. 4 is a plan view of the wedge employed. Fig. 5 is a side elevation of said wedge.

Like numerals of reference indicate like parts in all the figures of the drawings.

Referring to said drawings, 1 1 designate the two sections of the pedestal, 2 2 the sections of the top, 3 3 the bridge pieces which are secured to the pedestal sections, and 4 4 the bridge-blocks by which the top sections are secured to the bridge-pieces. Each movable section of the table therefore comprises the usual number of parts, to wit: the pedestal section and its bridge-piece and block, and a top section or table-leaf which is secured to said block. With the exception of the bridge-block these parts are of the ordinary construction. In the present instance I prefer to make the bridge-block of metal, but as will be obvious hereinafter the customary wooden block could be employed. The bridge-block herein shown is made of sheet metal bent into substantially Z-shape in cross-section so as to provide the attaching flanges 5 at its opposite edges. These sheet metal bridge-blocks or angle plates not only possess the advantage of being lighter than the usual wooden blocks, but also provide a harder engaging surface for the wedges hereinafter referred to. Four of these bridge-blocks or angle plates are employed, as is usual, two for each section of the table, and as a set of my improved adjusting devices is applied to each bridge-block or angle plate a description of one will, of course, answer for all, the same reference numerals being used in each instance.

In attaching the bridge-block or angle plate it is rigidly secured by its upper flange to the underside of the table top with wood-screws, as indicated in Figs. 2 and 3, and by its lower or base-flange is connected to the bridge-piece 3 through the medium of bolts and winged nuts 6 and 7, respectively, two of which are employed and located near the opposite ends of said base-flange. This latter connection permits of a separation of the parts 3 and 4 at either or both ends by manipulating the winged nuts and in conjunction with a wedge 7 inserted between said parts at one end thereof so that the vertical disposition of the pedestal section can be changed with relation to the bridge-block or angle plate. Inasmuch as it is usual for the pedestal sections to separate or spread apart at their lower ends the wedges in practice are inserted at the outer ends of the parts 3 and 4, and, as will be obvious, the spreading of these latter parts at this point will tend to

move the lower end of the pedestal section inward or towards the companion pedestal section.

In the operation of the wedge the nut on the bolt at the outer end of the parts 3 and 4 is first loosened slightly and the wedge is then driven in until it binds tightly and will of course depress the outer end of the bridge-piece 3 and move the lower end of the pedestal section inward, and if this adjustment is not sufficient the operation is repeated until the desired adjustment is had. The binding of the wedge between the parts will hold the adjustment by frictional contact, and of course additional frictional engagement may be secured by roughening the surfaces of the wedge. In adjusting the parts by driving in the wedge the bolt-head at the inner end of said parts become the fulcrum for the flange 5 of the bridge-block or angle-plate, and of course the driving of the wedge tends to separate the parts at the inner ends thereof. Therefore, by adjusting the nut on said fulcrum-bolt it is possible also to adjust the upper end of either pedestal section to bring it on a line with the other or companion section. It will be seen, therefore, that the devices described provide for adjusting the pedestal sections both vertically and laterally, to thereby produce a close and even joint between said sections, and so that the ornamentations or beads on one will aline with those on the other.

Though an ordinary plain wedge may be employed I prefer to use one of the construction herein shown and described, as it is lighter and will keep in proper alinement with the base-flange while being driven and in use. For these purposes the wedge comprises a longitudinally slotted plate forming the body and provided at its opposite longitudinal edges with flanges 9 the upper edges of which are inclined as shown, and at the smaller end of the wedge, at opposite sides thereof, are formed ears 10 which are adapted to embrace the edges of the flange 5 and form guides for the wedge. The longitudinal slot at the center of the wedge is for the passage therethrough of the bolt 6, and said bolt therefore serves as an additional means for holding the wedge and keeping it in alinement.

Having described my invention, what I claim as new and desire to secure by Letters-Patent, is:—

1. In a pedestal extension table, the combination with opposite table sections connected to move to and from each other, and each comprising a top section, a pedestal section, and a connecting piece attached to and lying between the same, of bolts securing said connecting piece to one of said sections and located near the opposite ends of said piece, and a wedge interposed between said connecting piece and said latter section and

having retaining ears at its longitudinal edges adapted to bear on each side of said connecting piece.

2. In a pedestal extension table, the combination with opposite table sections connected to move to and from each other, and each comprising a top section, a pedestal section, and a connecting piece attached to and lying between the same, of bolts securing said connecting piece to one of said sections and located near the opposite ends of said piece, and a wedge interposed between said connecting piece and said latter section and having a longitudinal slot through which passes one of the retaining bolts, and retaining ears at the smaller end of said wedge adapted to bear on each side of said connecting piece.

3. In a pedestal extension table, the combination with opposite table sections connected to move to and from each other, and each comprising a top section, a pedestal section, and a connecting piece attached to and lying between the same, of bolts securing said connecting piece to one of said sections and located near the opposite ends of said piece, and a wedge interposed between said connecting piece and said latter section and comprising a plate having a longitudinal slot to receive one of the retaining bolts, inclined walls at the opposite longitudinal edges of the plate, and retaining ears at the smaller end of the wedge adapted to bear on each side of said connecting piece.

4. In a pedestal extension table, the combination with opposite table sections connected to move to and from each other, and each comprising a top section, a pedestal section, and an angle plate attached to one of said sections and having a horizontal flange portion, of bolts securing said flange portion to the other of said sections and located near the ends of said portion, and a wedge interposed between said flange portion and said latter section at one end of said portion.

5. In a pedestal extension table, the combination with opposite table sections connected to move to and from each other, and each comprising a top section, a pedestal section, and an angle plate attached to one of said sections and having a horizontal flange portion, of bolts securing said flange portion to the other of said sections and located near the ends of said portion, and a wedge interposed between said flange portion and said latter section at one end of said portion and having a slot through which passes one of the retaining bolts.

6. In a pedestal extension table, the combination with opposite table sections connected to move to and from each other, and each comprising a top section, a pedestal section, and an angle plate attached to one of said sections and having a horizontal flange portion, of bolts securing said flange portion to the other of said sections and located near

the ends of said portion, a wedge interposed between said flange portion and said latter section at one end of said flange portion and having a longitudinal slot through which 5 passes one of the retaining bolts, and opposite ears on the wedge embracing the edges of the angle plate.

In testimony whereof I have signed my name to this specification in the presence of two subscribing witnesses.

FRANK J. SENG.
